UNITED STATES PATENT OFFICE.

HERBERT Q. MARTIN, OF MILWAUKEE, WISCONSIN.

SAFE LOCK.

Application filed March 14, 1927. Serial No. 175,258.

This invention relates to locks, and is particularly directed to a safe lock.

It frequently happens that safes are locked with one of the bank employees within 5 the safe. This condition is aggravated by the fact that it also frequently occurs that the man locked within the safe is the only one who knows the combination of the safe and thus his removal from the safe is 10 accomplished only with extreme difficulty.

This invention is designed to overcome the defects noted above and objects of such invention are to provide a novel form of safe lock which is so constructed that it 15 may be operated from the inner side by normally removed means capable of application to the standard lock as an attachment and to construct the means so that a slight difference exists between the setting of the 20 outer and inner dials, such difference being a permanent amount and known to the operator who knows the combination of the safe.

Further objects are to provide a very simple form of attachment which may be applied to standard locks with a minimum alteration of the lock, it being merely necessary to drill a few holes in the casing of the 25 lock and to position the device thereon.

An embodiment of the invention is shown 30 in the accompanying drawings in which:

Figure 1 is a fragmentary view showing a section through a safe door diagrammatically, and showing a safe lock with parts 35 broken away and with the attachment in place and partly in section;

Figure 2 is a view somewhat similar to Figure 1 showing the plate in position which is normally employed to close the aperture 40 through the attachment;

Figure 3 is a sectional view on the line 3—3 of Figure 1;

Figure 4 is a rear view of the structure shown in Figure 1;

Figure 5 is a sectional detail showing the attachment in place.

Referring to the drawings, it will be seen that a safe door 1 has been shown as equipped with a tumbler lock, the casing 2 thereof being secured to the inner side of the door. This lock is operated by means of a tumbler shaft 3 projecting through the safe door and provided with a manipulating knob 4 and a graduated dial 5. Ordinarily, as in the standard construction 55 this tumbler shaft is keyed to one of the

discs and projects slightly beyond the last disc 6, the rear end of the key being indicated by the reference character 7. The casing has a hole drilled therein in alignment 60 with the tumbler shaft, as shown in Figure 1, and a circular cup 8 is secured in place in any suitable manner, as by means of rivets, as shown in Figure 1. This cup-shaped member is provided with a graduation or 65 notch 8' in one portion thereof, as shown in Figure 4, for the starting point. This cup 8 normally receives a closure plate 9 removably held therein, preferably by means of a split sleeve 10 inserted through the aperture in the cup and the aperture in the casing 2 of the lock, as shown in Figure 2. If desired, this removable plate may be provided with a handle 11. This plate is used merely to close the cup and the aperture and 70 keep dust out of the lock under normal conditions. The attachment comprises a dial 12 graduated similarly to the dial 5 and provided with a short hub 13, as most clearly shown in Figure 5. An extension sleeve 14 75 is pinned to the hub 13 and is slotted at one point for the reception of the end of the key 7. This dial 12 is thus rigid with the extension sleeve 14, and is adapted for operative connection with the tumbler shaft at the rear of the lock, by merely removing the plate 9 and inserting the device, as shown in Figure 1. The dial 12 is provided with 80 a manipulating knob 15, as indicated.

In making the attachment, the sleeve 14 90 is positioned upon the hub 13 and the two dials 5 and 12 are turned out of register by a predetermined amount, for example ten points, as indicated in Figure 1. Thereafter a hole is drilled through the sleeve 14 95 and the hub 13, and a pin 16 is driven into place, thus permanently locking the sleeve to the dial and holding the dial 12 in a predetermined relation to the dial 5 when the device is in operative position. This mode of construction is followed as the position of the key 7 frequently varies with reference to the dial 5 and by means of the construction outlined immediately above, it is possible to exactly position one dial with reference to 105 the other in a simple and easy manner.

It will be seen therefore that a very simple type of device has been provided which normally is removed from the lock and is adapted for cooperative attachment thereto 110 when required, and it will be seen further that due to the offsetting of the scale of one

dial with reference to the scale of the other dial, that a device has been provided which can not be freely manipulated by anyone to open the lock, but can be manipulated only by one apprised of this difference in setting of the two dials.

It will be seen further that the attachment can be readily applied to standard safe locks with a minimum of change to the 10 lock as all that is necessary is to drill the cover of the casing and position the parts as described.

Although the invention has been described in considerable detail, such description is 15 intended as illustrative rather than limiting as the invention may be variously embodied and as the scope of such invention is to be determined as claimed.

I claim:

20 1. The combination of a safe lock provided with a tumbler shaft, a casing surrounding said lock and having a hole therein in alignment with the tumbler shaft, a main dial carried by the outer end of said tumbler 25 shaft, and an auxiliary dial having a sleeve adapted for positioning through the aperture in said casing, said sleeve and the rear end of said tumbler shaft having cooperating 30 portions for operatively connecting said shaft and said sleeve.

2. The combination of a safe lock provided with a tumbler shaft, a casing surrounding said lock and having a hole therein in alignment with the tumbler shaft, a main 35 dial carried by the outer end of said tumbler shaft, and an auxiliary dial having a sleeve adapted for positioning through the aperture in said casing, said shaft having a key

therein and said sleeve having a notch adapted to receive said key. 40

3. The combination of a safe lock provided with a tumbler shaft, a casing surrounding said lock and having a hole therein in alignment with the tumbler shaft, a main 45 dial carried by the outer end of said tumbler shaft, and an auxiliary dial having a sleeve adapted for positioning through the aperture in said casing, said sleeve and the rear end of said tumbler shaft having cooperating 50 portions for operatively connecting said shaft and said sleeve, said dials having graduations thereon with the graduations of one dial offset a predetermined amount with reference to the scale of the other dial. 55

4. The combination of a safe provided with a tumbler lock having a tumbler shaft provided with an outer manipulating member equipped with a dial, said lock having a casing provided with an aperture, a cup-shaped member secured to the rear face of 60 said casing adjacent said aperture, and a removable attachment provided with a manipulating knob and a dial attached for positioning within said cup-shaped member, said attachment having a sleeve adapted to 65 project through said aperture, said sleeve and said tumbler shaft having interengaging parts to position one dial at a predetermined angular setting with reference to the other dial. 70

In testimony that I claim the foregoing I have hereunto set my hand at Milwaukee, in the county of Milwaukee and State of Wisconsin.

HERBERT Q. MARTIN.
